LIP STICK

Maurice E. Lessin, Bronx, N. Y., assignor to Parfums Corday, Inc., New York, N. Y., a corporation of New York

Application September 15, 1934, Serial No. 744,159

9 Claims. (Cl. 132—79)

This invention relates to lipsticks and the like articles.

An object of this invention is to provide a device of the character described having a cover provided with a mirror adapted to move into position for use upon removal of the cover, provision being made for retaining the mirror within the cover when the lipstick is not in use.

A further object of this invention is to provide a neat, compact and attractive device of the character described, comprising comparatively few and simple parts, which shall be relatively inexpensive to manufacture, smooth and positive in operation, and withal practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a perspective view of a lipstick embodying the invention with parts broken away to show the interior construction;

Fig. 2 is a front elevational view of my improved lipstick with a portion of the cover broken away and the mirror in position for use;

Fig. 3 is a cross-sectional view taken on line 3—3 of Fig. 2;

Fig. 4 is a view somewhat similar to Fig. 2 but showing the mirror in collapsed position;

Fig. 5 is a cross-sectional view taken on line 5—5 of Fig. 4;

Fig. 6 is a cross-sectional view taken on line 6—6 of Fig. 4;

Fig. 7 is a perspective view of my improved lipstick with the cover removed;

Fig. 8 is a front elevational view of a lipstick embodying the invention and illustrating a modified construction, with parts broken away to show the interior construction; and

Fig. 9 is a cross-sectional view taken on line 9—9 of Fig. 8.

Referring now in detail to the drawing, 10 designates a lipstick embodying the invention and comprises a holder 11 and a cover 12 therefor. The holder 11 comprises a base 13 from which there extends upwardly a tubular portion 14 which may be of rectangular cross-section and having a front wall 15 provided with an elongated

longitudinal slot 16. Slidably mounted within the tubular member 14 is a cup-shaped member 18 receiving the lower end of a stick of lip rouge 19. Fixed to the cup 18 is a knob 20 projecting through the slot 16 and adapted to be engaged by the thumb of the user for pushing the stick of lip rouge upwardly to expose a portion thereof for use.

The base 13 is preferably of greater cross-section than the tubular portion 14, providing a shoulder or ledge 22 at the upper end of the base. For the purpose hereinafter appearing, the ledge 22 is provided with a thin, narrow slot 24 adjacent

the front wall 15 of the tubular portion 14 and on one side of the base. Fitted over or telescoping with the tubular portion 14 is a cover member 25 open at the bottom and preferably likewise of rectangular cross-section. Said cover is provided with a top wall 26, side walls 27 and 28, front walls 29 and a rear wall 30. The side wall 28 is formed adjacent the front wall 29 with an elongated slot 32 extending to the lower edge of the cover.

Fixed to a corner of the front wall 29 of the cover adjacent top wall 26 and side wall 28 and extending inwardly from said front wall, is a pin 35. Pivoted to the pin 35 and disposed between front wall 29 and tubular portion 14, is a mirror 36 adapted to pass through the slot 32 and having substantially the shape of the front wall 29. The mirror 36 is provided at one upper corner thereof with an apertured ear 38 receiving the pin 35. At the lower end thereof said mirror 36 is formed with a lug 39, for the purpose hereinafter appearing. The mirror 36 may be made of metal or glass and may optionally be provided with a frame 40. Preferably the lug 39 projects below the lower edge of the cover 25.

There is also mounted on the pin 35 a coil torsion spring 43 having one arm 44 engaging the undersurface of the top wall 26, and a second arm 45 contacting the upper edge of the mirror or soldered thereto. It will now be understood that normally when the cover is removed from the holder, the torsion spring 43 will move the mirror through the slot 32 into horizontal position. However, the mirror 36 may be pressed back through the slot 32 within the cover and the cover then placed over the tubular portion 14, the lug 39 entering the slot 24. The lower edges of the cover 25 preferably contact the ledge 22 of the base 13. The engagement of the lug 39 within the slot 24 will hold the mirror within the cover when the lipstick device is assembled. However,

upon pulling the holder downwardly from out of

the slot 24, the lower edge of the cover 25 will be urged upwardly by the torsion spring 43, the lug 39 entering the slot 24. The lower edges of the cover 25 preferably contact the ledge 22 of the base 13. The engagement of the lug 39 within the slot 24 will hold the mirror within the cover when the lipstick device is assembled. However,

upon pulling the holder downwardly from out of

the slot 24, the lower edge of the cover 25 will be urged upwardly by the torsion spring 43, the lug 39 entering the slot 24. The lower edges of the cover 25 preferably contact the ledge 22 of the base 13. The engagement of the lug 39 within the slot 24 will hold the mirror within the cover when the lipstick device is assembled. However,

upon pulling the holder downwardly from out of

the slot 24, the lower edge of the cover 25 will be urged upwardly by the torsion spring 43, the lug 39 entering the slot 24. The lower edges of the cover 25 preferably contact the ledge 22 of the base 13. The engagement of the lug 39 within the slot 24 will hold the mirror within the cover when the lipstick device is assembled. However,

upon pulling the holder downwardly from out of

the slot 24, the lower edge of the cover 25 will be urged upwardly by the torsion spring 43, the lug 39 entering the slot 24. The lower edges of the cover 25 preferably contact the ledge 22 of the base 13. The engagement of the lug 39 within the slot 24 will hold the mirror within the cover when the lipstick device is assembled. However,

upon pulling the holder downwardly from out of

the slot 24, the lower edge of the cover 25 will be urged upwardly by the torsion spring 43, the lug 39 entering the slot 24. The lower edges of the cover 25 preferably contact the ledge 22 of the base 13. The engagement of the lug 39 within the slot 24 will hold the mirror within the cover when the lipstick device is assembled. However,

upon pulling the holder downwardly from out of

the slot 24, the lower edge of the cover 25 will be urged upwardly by the torsion spring 43, the lug 39 entering the slot 24. The lower edges of the cover 25 preferably contact the ledge 22 of the base 13. The engagement of the lug 39 within the slot 24 will hold the mirror within the cover when the lipstick device is assembled. However,

the cover, the mirror will automatically spring into position for use.

It will now be understood that the user may remove the lipstick holder, hold the cover in one hand and then use the lipstick, mirroring her lips in the mirror 36.

In Figs. 8 and 9 there is shown a modified construction. The device 10a shown in Figs. 8 and 9 comprises a holder 11a and a cover 12a. The holder 11a is similar to the holder 11 except that the former is provided with a central slot 24a instead of a slot located on one side as in the latter. The cover 12a is provided with a rear wall 50, side walls 51 and a top wall 52, and is open at the bottom. The front wall of the cover is in the form of a plate 53 having a mirrored inner surface and is hinged, as at 54, to the front edge of the top wall 52. A coil torsion spring 55 mounted on the hinged pin normally tends to retain the plate 53 in the upstanding vertical position shown in the dot dash lines of Fig. 9 with the inner mirrored surface thereof exposed. The plate 53, however, is provided with a lug 57 at the lower end thereof adapted to be received within the slot 24a for retaining the same in folded position. It will now be understood that upon removing the cover, the torsion spring 55 will lift the plate 53 so that the inner mirrored surface thereof is exposed to view for use.

It will thus be seen that there is provided a device in which the several objects of this invention are achieved, and which is well adapted to meet the conditions of practical use.

As various possible embodiments might be made of the above invention, and as various changes might be made in the embodiments set forth, it is to be understood that all matter herein set forth or shown in the accompanying drawing, is to be interpreted as illustrative and not in a limiting sense.

Having thus described my invention, I claim as new and desire to secure by Letters Patent:

1. In combination with a device of the character described, comprising, a cosmetic holder, and a cover therefor, a mirror disposed within said cover and hinged thereto, spring means for pivotally moving said mirror with respect to said cover to eject said mirror from said cover, and means on said holder for retaining said mirror within said cover against the action of said spring means.

2. In combination, a lipstick holder comprising a base, a tubular member extending upwardly therefrom, said base having a ledge at the upper end thereof, a cover telescoping with said tubular member and having a longitudinal slot, and a pin fixed to a wall of said cover, a mirror hinged to said pin, said mirror being disposed within said cover and adapted to move through said slot, a torsion spring on said pin adapted to move said mirror out of said slot, and said base having a slot extending in the ledge thereof, said mirror

being provided with a projection adapted to be received within said base slot upon assembling the holder with the cover to retain the mirror within said cover.

3. In combination with a cosmetic holder having a cover therefor, a mirror hinged to said cover, means on said holder for retaining the mirror within said cover, and said mirror being pivotally movable out of said cover upon withdrawing the cover from said holder.

4. In combination with a lipstick holder having a separable cover open at the bottom for telescoping therewith, a mirror on said cover normally hidden from view and spring means for moving said mirror to exposed position upon removing the cover from the holder.

5. In combination, a lipstick holder, a cover therefor, a member having a mirrored surface disposed between said cover and said holder when the holder is covered, said holder having means to retain said member within said cover when said holder and cover are assembled and spring means for moving said member relatively to said cover to expose said mirrored surface upon disassembling said cover and holder.

6. In a device of the character described, a holder comprising a base and a tubular portion extending therefrom, a separable cover receiving said tubular portion, one wall of said cover being hinged thereto and tending normally to turn outwardly therefrom, and coacting means on said wall and holder for retaining said wall in closed position.

7. In a device of the character described, a holder comprising a base and a tubular portion extending therefrom, a separable cover receiving said tubular portion, one wall of said cover being hinged thereto and adapted to be turned outwardly therefrom, coacting means on said wall and holder for retaining said wall in closed position, and spring means for pivotally moving said wall to expose the inner surface thereof upon removal of the cover from said holder.

8. In combination with a lipstick holder having a separable cover therefor, a member having a mirrored surface disposed between said cover and said holder when the holder and cover are in assembled relationship, means for retaining said member in said last named position, and spring means for automatically moving said member relatively to said cover to expose said mirrored surface upon disassembling said cover and holder.

9. In combination with a lipstick holder having a separable cover adapted to be slidably connected thereto, a member having a mirrored surface disposed inside of said cover, said member being pivotally mounted to said cover, and means whereby a predetermined amount of sliding of the cover away from the holder will cause said member to be pivotally swung to a position outside of said cover at an angle to its former position.

MAURICE E. LESSIN.
